UNITED STATES PATENT OFFICE.

GEORGE W. BINGHAM, OF NEW YORK, N. Y.

MOVING-PICTURE MACHINE.

Application filed September 6, 1924. Serial No. 736,205.

To all whom it may concern:

Be it known that I, GEORGE W. BINGHAM, a citizen of the United States, and a resident of the city, county, and State of New York, have invented certain new and useful Improvements in Moving-Picture Machines, of which the following is a specification.

This invention relates to moving picture machines in general, but more particularly to projectors where the requirement for accurate registration and "framing" is an important factor.

Special objects of the invention are to provide efficient mechanism of a simple and practical form for effecting accurate registration of the pictures and, when occasion requires, the quick "framing" of the pictures and return to normal, accurate registration.

Other objects of the invention and the novel features of construction by which the same are attained are disclosed in the following specification.

In the drawing accompanying and forming part of the specification, the invention is illustrated embodied in but one of its many possible commercial forms and it should therefore be understood that the structure may be modified from this disclosure without departure from the broad spirit and scope of the invention as hereinafter defined and claimed.

Figure 1 is a broken side elevation and part sectional view of a projector having features of the invention incorporated therein.

Figure 2 is a rear view of the same with portions of the framing mechanism shown in section.

Figure 3 is an enlarged horizontal sectional view on substantially the central plane of the feed roll.

Figure 4 is a further enlarged cross sectional view on substantially the plane of line 4-4 of Figure 3.

The machine illustrated is of the beater type in which the film indicated at 5 is advanced by an oscillating beater 6 operating in conjunction with cooperating continuously rotating take-up rolls 7, 8. A similar pair of cooperating feed rolls 9, 10 are shown located above the gate 11 for maintaining a loop for the intermittent film advancing mechanism to operate upon.

One of the feed rolls of each pair, designated 7 and 9, is shown as of expandable construction for the purpose of effecting variations in the film feed and the cooperating rolls 8, 10 are arranged to accommodate themselves to such adjustments as by being journaled in swinging brackets 12, pivoted at 13 and acted on by the springs 14.

The peripherally adjustable rolls 7, 9 may be of duplicate construction and made after the manner disclosed in my Patent 1,508,673, each of four segments 15, 16, 17, 18, guided for radial adjustment on the supporting shaft 19 by the angularly related transverse pins or keys 20, 21. These cylindrical segments are of conical formation inside to receive an expanding cone 22 as in the patent referred to, but in the present disclosure, the roll is considerably longer than the width of the film as clearly shown in Figure 3 so that the conical surfaces are of increased length, allowing for a much less acute angle and longer bearing surfaces.

This lessened angularity makes possible a much finer and more accurate adjustment of the roll and provides also an easier sliding action in the relative adjustment of the conical parts. The adjusting cone has an easy sliding fit over the supporting shaft 19 and is longitudinally slotted at 23, 24, for passage of the radial segment holding pins 20, 21. The cone is shown secured by transverse pin 25 on a shaft section 26 co-axial with the roll shaft 19 and forming in effect a longitudinally shiftable extension of the same.

A bearing is provided for the longitudinally shiftable cone carrying section of the shaft shown as a bearing sleeve 27 formed with an external screw thread 28 and engaged in a corresponding screw seat 29. The inner end of this sleeve forms an abutment engaging the outer end of the cone and therefore serves by its adjustment inward, to effect an expansion of the roll segments and by adjustment outward, to enable a contracting or collapsing movement of the roll segments.

The roll segments are held closely engaged over the cone and forced to follow the adjusting movements of the cone by an elastic encircling band 30 of rubber or the like shown seated in a peripheral

groove 31 formed in the outer surface of the segments. This elastic ring is shown as of approximately the full picture width of the film strip so as to afford a frictional grip on the intermediate portion and substantially the full width of the strip and also to operate in effect as a "wiper" for keeping the picture portion of the film clean and free of dust or other foreign matter.

The adjusting sleeve is shown provided with a head 32 on the outer end of the same, forming a fingerhold by which the same may be readily adjusted and it will be seen that by turning this screw in one direction or the other, the cone will either be forced inward to wedge the roll segments apart or permitted to shift outward to allow a collapsing movement of the segments, thus increasing the peripheral speed of the roll in the one instance and reducing such speed in the other instance, whereby to effect an increase or reduction in the film movement. This construction provides for very fine and accurate adjustments and hence enables absolute registration. As the upper and the lower variable rolls are independently adjustable, the machine can be quickly adjusted to regulate either the length of feed or the size of the loop, or both, as may be desired.

For framing purposes, provision is made for effecting a quick change in the peripheral speed of the film advancing roll and the means for such purpose comprises in the present disclosure, a shift lever 33 pivoted on the frame of the machine at 34 and having a rotatable engagement with the end of the cone shaft 26 in the form of a yoke 35 engaging in a groove way 36 in the end portion of the shaft and swiveled on the lever at 37. This lever is normally swung outwardly into the position indicated in full lines in Figure 3, by a spring 38 where the cone is held rotatably engaged with the end of the positioning screw 27, said screw serving thus in effect as an adjustable stop, determining the outward position of the cone and hence the normal running condition of the feed roll.

It will be seen from the foregoing that the feed roll may be readily adjusted for registration purposes at any time by simply turning the adjusting sleeve to either increase or reduce the peripheral speed of the roll and that for framing purposes, the lever can be thrust inward more or less to effect a quick enlargement of the roll and hence a sudden "over-feeding" of the film sufficient to advance the film a picture length or more and thus a proper framing of the picture. It will be seen also that immediately the framing is effected, the lever will be automatically returned and the roll restored to the previously registered proper running condition. Thus the framing is effected

without destroying or in any way impairing previous adjustments made for purposes of registration.

The combination of the framing and registering mechanisms in practically one and the same device very materially simplifies the construction and operation of the machine and by the elimination of parts, makes the action more accurate and positive and materially reduces the cost of production.

What is claimed is:

1. In moving picture apparatus, film advancing mechanism including means regulatable to vary the film feed while the machine is in operation, a registering device for effecting a fine adjustment of said means for registering purposes, an independently operable framing device for effecting coarser adjustments of said means for framing purposes and restoring means for automatically effecting return of the regulatable means to previously registered condition after each actuation of the framing device.

2. In moving picture apparatus, film advancing mechanism including a feed roll of peripherally variable speed, means for effecting gradual adjustments of the peripheral speed of said roll for registering purposes, means for independently effecting sudden adjustments of said roll for framing purposes and restoring means for automatically returning said roll to the previously registered condition after each framing operation.

3. In moving picture apparatus, film advancing mechanism including an expansible roll, means for effecting a fine adjustment in the peripheral size of said expansible roll and means for independently effecting coarser adjustments in the peripheral size of said roll.

4. In moving picture apparatus, film advancing mechanism including an expansible roll, means for effecting a fine adjustment of said expansible roll, means for independently effecting coarser adjustments of said roll and spring means for automatically restoring the roll to the condition previously effected by the fine adjusting means after each operation of said coarser adjusting means.

5. In moving picture apparatus, a film advancing roll of peripherally variable speed, means for effecting relatively fine adjustments in the peripheral speed of said roll and independent means for effecting coarser and quicker adjustments in the peripheral speed of the roll, said finer adjusting means including a regulatable stop and a part engaged thereby to limit the peripheral speed adjustment and means for automatically returning said part to said stop after each actuation of the coarser adjusting means.

6. In moving picture apparatus, an expansible film feeding roll, an expander there-

- for, an adjustable stop for positioning said expander and means for shifting the expander independently of said stop. 65
7. In moving picture apparatus, an expansible film feeding roll, an expander therefor, an adjustable stop for positioning said expander, means for shifting the expander independently of said stop and means for automatically returning the expander to the position determined by said adjustable stop. 70
8. In moving picture apparatus, an expansible film feeding roll, an expander therefor, an adjustable stop for positioning said expander and means for shifting the expander independently of said stop, including a swinging lever having pivotal connections with said expander. 75
9. In moving picture apparatus, an expansible film feeding roll, an expander therefor having a shaft extension, an adjustable stop for positioning said expander and a handle connected with the shaft extension for shifting the expander independently of the stop. 80
10. In moving picture apparatus, an expansible film feeding roll, an expander therefor having a shaft extension, an adjustable stop for positioning said expander, a handle connected with the shaft extension for shifting the expander independently of the stop and spring means for automatically returning the handle and shaft extension. 85
11. In moving picture apparatus, an expansible film feeding roll, an expander for said roll having a shaft extension, an adjustable screw sleeve surrounding said shaft extension and forming an abutment for the expander and shifting means for the expander engaged with said shaft extension for shifting the expander independently of the screw sleeve. 90
12. In moving picture apparatus, a segmental expansible film feeding roll provided with resilient means for contracting the same, a cone for separating the segments, a shaft extending from said cone, a sleeve surrounding the shaft and adjustable to position the cone and shifting means engaged with the shaft for shifting the cone independently of said sleeve. 95
13. In moving picture apparatus, a roll shaft, expansibly related roll segments keyed on said shaft, a cone for expanding the segments slidably engaged over said shaft and provided with a concentric shaft extension, an adjusting screw for positioning said cone and a shifting device having a relatively rotatable engagement with the shaft extension for shifting the cone independently of the adjusting screw. 100
14. In moving picture apparatus, a roll shaft, expansibly related roll segments keyed on said shaft, a contracting ring sur- 105
- rounding said segments, a cone for expanding the segments slidably related to the shaft and provided with a shaft extension, a screw sleeve forming a bearing for said shaft extension and engaged by the cone and a swinging lever having a relatively rotatable connection with the end of the shaft extension. 110
15. In moving picture apparatus, a roll shaft, expansibly related roll segments keyed on said shaft, a contracting ring surrounding said segments, a cone for expanding the segments slidably related to the shaft and provided with a shaft extension, a screw sleeve forming a bearing for said shaft extension and engaged by the cone, a swinging lever having a relatively rotatable connection with the end of the shaft extension and spring means for automatically returning said lever and shaft extension to restore the engagement of the cone with the end of the screw sleeve. 115
16. In motion picture apparatus, an expansible film feeding roll of considerably greater length than the width of the film which it feeds and comprising roll segments having inclined inner surfaces of the slight angle afforded by utilizing the full length of the over-size roll, an expanding wedge of correspondingly slight incline engaged with the inclined inner surfaces of the roll segments, means for contracting the roll segments upon said wedge and means for shifting the wedge, including an adjustable abutment for positively forcing the wedge in one direction and spring means for returning the wedge into engagement with said abutment. 120
17. In moving picture apparatus, a film feeding roll of hard non-resilient material having a resilient film contacting surface intermediate the ends of the same, projecting when free above the non-resilient end portions of the roll, of substantially the full width of the picture section of the film but of less extent than the total width of the film so as to engage only the intermediate picture section of the film and not contact with the edge portions of the film, thereby leaving such edge portions free for engagement by the hard non-yielding end parts of the roll. 125
18. In moving picture apparatus, film advancing means and independently operable screw and lever mechanisms respectively for effecting a fine gradual adjustment in the film feeding action of said advance means for registration purposes or coarser sudden variations in the film feeding action of the advancing means for framing purposes. 130

In witness whereof, I have hereunto set my hand this 25th day of July, 1924.

GEORGE W. BINGHAM.
